UNITED STATES PATENT OFFICE

SAMUEL S. MATTHES, OF MANSFIELD, OHIO, ASSIGNOR TO THE OHIO BRASS COMPANY,
OF MANSFIELD, OHIO, A CORPORATION OF NEW JERSEY

SECTION INSULATOR

Application filed October 15, 1928. Serial No. 312,436.

My invention relates to section insulators and particularly to insulators for use in connection with trolley conductors.

The principal object of my invention is 5 to provide a device of the character described in which the wearing portions can be removed and replaced easily, quickly and economically when desired and without the necessity of any changes or disturbances of the 10 trolley conductor.

Other objects will be noted as I further describe my invention.

My invention resides in the new and novel construction, combination and relation of the 15 various parts hereinafter described and shown in the drawing accompanying this specification.

In the drawing:—

Fig. 1 is a side view of my invention showing 20 trolley wires attached thereto.

Fig. 2 is a top view of Fig. 1.

Fig. 3 is a section on the line 3—3 of Fig. 2.

Figs. 4, 5 and 6 are sections on the lines 4, 5 and 6 respectively of Fig. 1.

25 In the preferred embodiment of my invention I employ an insulating bar 1 preferably of wood and provided with a threaded clevis shaped member 2 secured to the member 1 by means of the through bolt 3 and which is used to secure the device to an overhead support when desired.

To each end of the insulating member 1 is a clevis shaped end member 4 secured to the body member 1 by means of the through 35 bolts 5. Each end member is provided with a diagonally positioned passage 6 in which is positioned the adjacent ends of the trolley wire 7. The trolley wire is held in position by means of the two set screws 8 threadably secured to the end member 4 and which may be supplied with cone- or cup-shaped points for engagement with the trolley wire. The outer end of the member 4 is provided with a transverse passage to receive a through bolt 40 9. The inner end of the member 4 is provided

with a projecting lip or ear 10, which connects the projecting side plates 11, forming a clevis shaped pocket in which the end of the insulating bar 1 is positioned and held in place by the through bolts 5 as mentioned. The projecting lip or ear 10 acts as a compression member to resist a tendency for the end of the member 4 to tip upwardly, due to the longitudinal tension placed upon the trolley wire 7.

To the outer end of the end member 4 is detachably secured a wear-member 12 which is of a U-shaped formation as shown in Fig. 5 and is provided with a pair of spaced lips 13 with registering passages therein to register with the passage through the outer end of the member 4 and to receive therein the bolt 9 which secures the members 4 and 12 together approximately midway the member 12. The member 12 is also provided with upwardly and inwardly extending and spaced hook shaped members 14.

The underface of the wood member 1 is provided with a groove 15 in which is positioned an insulating member 16 which may be of wood or other insulating material and which extends between the ends of the spaced members 12 and forms with the removable member 12 a smooth and straight under-run 70 for a passage of the current collector from one trolley wire to the other. The members 12 and 16 are subjected to considerable wear and burning due to the passage of the current collector across the insulator and therefore it becomes desirable to renew and replace 75 these members and I have so arranged.

In order to properly maintain the inner ends of the members 12 in position and the ends of the member 16, I employ a U-shaped member 17 provided with lugs 18, which are in turn provided with registering openings to receive the through bolt 19, which holds the member 17 in position and also consists in holding the end member 4 upon the insulating member 1. The holding member 17 80

is provided with a lower wear surface 20 which interlocks with the ends of the members 12 and 16 and forms a smooth under-run therewith. The ends of the members 12 and 16 are notched to receive the lower portion 20 of the member 17. As the portion 20 of the member 17 is subject to wear, it is possible that it may wear down sufficiently so that the portion which interlocks with the member 16 may be entirely worn away, in which case the member 16 would drop, therefore I provide an extra portion 21 which will still remain in position after the portion 20 has been worn away and will engage with the bevelled end of the member 16 and hold the member 16 in position for a further length of time.

The ends of the member 16 are reduced in cross-section as shown at 22 to interlock with recesses in the member 17.

The outer ends of the members 12 are furnished with a projecting member 23 which has a depending lip portion 24 forming a groove therein to receive the trolley conductor 7 and which is arranged to be bent around the trolley wire adjacent the end of the member 12, thereby producing a gradual and easy approach of the trolley wheel from the wire to the member 12. The member 23 is provided with transversely projecting and headed members 25 which interlock with the hook shaped members 14 and which are secured into position by first engaging the hook shaped portion 14 while the member 23 is in a substantially vertical position and the member 23 is then rotated down into position as shown, and as it is provided at its rear end with a cam-shaped portion 26 which engages with the trolley wire, the trolley wire will be placed down into position in contact with the inner surface of the member 12 and held in that position, and the lips 24 which underlap the trolley wire 7 hold the member 23 against rotating backwardly and releasing the trolley wire.

From the description given it will be apparent that the members 12, 16, 17 and 23 are all easily removable and releasable at will without seriously disturbing the trolley wire, its connection to the section insulator or without disturbing the section insulator proper comprising the insulating bar 1 and the end member 4.

In insulating the device, the trolley wire is first positioned in the passage 6 and held therein by means of the set screws 8. The member 12 is then placed in position and secured thereby the bolt 9. The insulating bar may then be placed in position between the ends of the members 12 and within the groove 18 and when so positioned, the holding yoke or member 17 is positioned and secured in place by the bolt 19. The end approach member 23 may then be positioned by interlocking it with the hook lugs 14 while it is in a

vertical position and then rotating the member to a horizontal position as shown in Fig. 3, and the lips 24 thereof bent around the trolley wire 7.

Having described my invention, I claim:—

1. A section insulator comprising an insulating bar, end members each provided with means to receive a trolley wire and having means to hold the trolley wire in place, means to hold the end members to the insulating bar, each end member having a renewable end wear-member detachably secured thereto, a renewable insulating wear member positioned below the insulating bar and extending between the ends of the first said renewable wear members, means detachably secured to the device to hold the adjacent ends of the insulating member and renewable end wear-members in position and other detachable wear-members secured to the outer ends of the renewable end wear-members to clamp the trolley wire between the renewable end wear-members and the detachable wear-members.

2. A section insulator comprising an insulating bar, end members each provided with means to receive a trolley wire and having means to hold the trolley wire in place, means to hold the end members to the insulating bar, each end member having a renewable end wear-member detachably secured thereto, a renewable insulating wear member positioned below the insulating bar and extending between the ends of the first said renewable wear-members, means detachably secured to the device to hold the adjacent ends of the insulating member and renewable end wear-members in position.

3. A section insulator comprising an insulating bar, end members secured to the bar and each provided with means to receive a trolley wire and means to hold the wire in place, each end member provided with a renewable wear-member, means to detachably secure the same in place and a renewable insulating member positioned between the ends of the renewable wear-members and supporting means securing the adjacent ends of the said renewable parts in alinement, the end wear-member being removable and replaceable without disturbing the said supporting means at its end adjacent the insulating member.

4. A section insulator comprising an insulating bar, end members secured to the bar and each provided with means to receive a trolley wire and means to hold the wire in place, each end member provided with a renewable wear-member, means to detachably secure the same in place, a renewable insulating member positioned between the ends of the renewable wear-members, means securing the said renewable parts in alinement and renewable members projecting from the outer end of each renewable wear-member to en-

- gage the trolley wire and detachably secured to the renewable wear-member.
5. A section insulator comprising an insulating bar, end members secured to the bar and each provided with means to receive a trolley wire and means to hold the wire in place, each end member provided with a renewable wear-member, means to detachably secure the same in place, a renewable insulating member positioned between the inner ends of the renewable wear-members and means securing the said renewable parts in alignment and means pivotally secured to a part of the wear members to engage and hold the trolley wire. 70
10. An end attachment for a trolley wire support comprising a body member and a renewable member detachably secured to the body member; the body member comprising spaced members to receive a supporting member, means to receive a trolley wire, adjustable means to hold the wire in place and the spaced members provided with means to secure the body member to the support; the renewable member comprising an elongated U-shaped member to receive the trolley wire, means to detachably secure the renewable member to the under side of the body member, a detachable and rotatable member interlocked with one of the members of the end attachment to secure the trolley wire in place relative to the renewable member and having projecting means to extend along the trolley wire beyond the renewable member and having a groove in which the wire is positioned and formed of bendable lips, and auxiliary holding means at one end of the renewable member to hold the renewable member in position relative to the body member. 80
20. An end attachment for a trolley wire support comprising a body member and a renewable member detachably secured to the body member; the body member comprising spaced parts to receive a supporting member, means to receive a trolley wire, adjustable means to hold the wire in place and the spaced parts provided with means to secure the body member to the support; the renewable member comprising an elongated part to receive the trolley wire, means to detachably secure the renewable member to the body member, auxiliary holding means at one end of the renewable member to hold the renewable member in position relative to the body member and means pivotally mounted on the renewable member to engage the trolley wire and force it into engagement with the renewable member when rotated and hold the trolley wire against displacement. 90
30. An end attachment for a trolley wire support comprising a body member and a renewable member detachably secured to the body member; the body member comprising spaced parts to receive a supporting member, means to receive a trolley wire, adjustable means to hold the wire in place and the spaced parts provided with means to secure the body member to the support; the renewable member comprising an elongated part to receive the trolley wire, means to detachably secure the renewable member to the body member, auxiliary holding means at one end of the renewable member to hold the renewable member in position relative to the body member and means pivotally mounted on the renewable member to engage the trolley wire and force it into engagement with the renewable member when rotated and hold the trolley wire against displacement. 100
40. An end attachment for a trolley wire support comprising a body member and a renewable member detachably secured to the body member; the body member comprising spaced parts to receive a supporting member, means to receive a trolley wire, adjustable means to hold the wire in place and the spaced parts provided with means to secure the body member to the support; the renewable member comprising an elongated part to receive the trolley wire, means to detachably secure the renewable member to the body member, auxiliary holding means at one end of the renewable member to hold the renewable member in position relative to the body member and means pivotally mounted on the renewable member to engage the trolley wire and force it into engagement with the renewable member when rotated and hold the trolley wire against displacement. 110
50. An end attachment for a trolley wire support comprising a body member and a renewable member detachably secured to the body member; the body member comprising spaced parts to receive a supporting member, means to receive a trolley wire, adjustable means to hold the wire in place and the spaced parts provided with means to secure the body member to the support; the renewable member comprising an elongated part to receive the trolley wire, means to detachably secure the renewable member to the body member, auxiliary holding means at one end of the renewable member to hold the renewable member in position relative to the body member and means pivotally mounted on the renewable member to engage the trolley wire and force it into engagement with the renewable member when rotated and hold the trolley wire against displacement. 120
60. An end attachment for a trolley wire support comprising a body member and a renewable member detachably secured to the body member; the body member comprising spaced parts to receive a supporting member, means to receive a trolley wire, adjustable means to hold the wire in place and the spaced parts provided with means to secure the body member to the support; the renewable member comprising an elongated part to receive the trolley wire, means to detachably secure the renewable member to the body member, auxiliary holding means at one end of the renewable member to hold the renewable member in position relative to the body member and means pivotally mounted on the renewable member to engage the trolley wire and force it into engagement with the renewable member when rotated and hold the trolley wire against displacement. 130
7. A renewable wear-member for a trolley wire support comprising an elongated member having a surface for contact with a moving current collector and a wire receiving channel open along its upper edge, means to secure the wear-member in position on the underside of a support and rotatable means at one end to force the trolley wire into position with the wear-member and to hold the trolley wire in a fixed position relative to the wear-member and means at the other end to be engaged by auxiliary means to secure the wear-member to a support. 75
9. A renewable wear-member for a trolley wire support comprising an elongated member having a surface for contact with a moving current collector and a wire receiving channel open along its upper edge, means to secure the wear-member in position on the underside of a support and rotatable means having a cam portion to engage the trolley wire to force it into position and mounted at one end of the wear-member to hold the trolley wire in a fixed position relative to the wear-member. 80
10. A renewable wear-member for a trolley wire comprising an open top member to receive a trolley wire secured to a supporting member, means to detachably secure the wear-member to the support, open-end undercut spaced lugs mounted at the end of the wear-member to receive a detachable wear-member. 85
11. A section insulator having a substantially smooth under-run comprising an insulating bar, end members fixed thereto and each provided with means to receive a trolley wire and having means to secure the wire in fixed relation to the end members, a renewable member for attachment to and detachment from the end members without disturbing the fixed relation of the aforesaid parts, means to detachably secure each wear-member to its end member and supporting means for the end of the wear-member, an insulating bridge member extending between the ends of the wear-members and supported by the supporting means, the bridge member and supporting means and wear-members providing a substantially smooth and uninterrupted path for a moving current connector and means on the supporting means engaging the end of the bridging member to hold the bridging member in place after the lower wear portion of the supporting means has been worn out. 95
12. A section insulator comprising an insulating bar, end members fixed thereto and each provided with means to receive a trolley wire and means to secure the wire in fixed relation to the end members, a renewable wear-member for each end member, a renewable bridge between the end member, a pivotally mounted renewable member secured to each wear-member, the wear-members, pivotally mounted members and bridge member arranged to be attached or detached without disturbing the trolley wire with respect to the end members and the insulating bar. 110
13. A section insulator for trolley wires, comprising an insulating bar, an auxiliary in-

ulating bridging member extending length-wise of the bar, supporting members for the bridging member to secure its ends to the bar and bolts to detachably secure the supporting members to the bar, end members secured to the ends of the bar, a detachable wear-member secured to each end member in alignment with the bridging member and receiving the trolley wire and an end approach member rotatably interlocked with each wear-member to engage the trolley wire and press the wire into position and so hold it relative to the wear-member.

10 In testimony whereof I affix my signature.
